UNITED STATES PATENT OFFICE

2,137,730

ENGINE

Clifton F. Smith, Memphis, Tenn.

Application August 16, 1937, Serial No. 159,206

9 Claims. (Cl. 121—117)

This invention relates to reciprocating engines employing a plurality of cylinders and pistons, the impulses for which pistons may be furnished either by steam from an external source, or by internal combustion.

The present embodiment, which is especially adapted for aeronautical purposes, has been confined, both in the drawings and the specifications, to an internal combustion engine. It will be 10 distinctly understood, however, that the construction outlined in a number of the claims is as readily applicable to a steam engine and is intended to be so construed.

It primarily relates to an engine construction in which the stroke is relatively long as compared with the bore of the cylinder and to the means by which the transfer of power impulses of the piston to the crank shaft is accomplished.

The primary object of the invention is to provide an engine which is simple in construction, durable, light in weight and capable of producing maximum power with minimum vibration.

A further object is to provide novel means in a long stroke cylinder construction for transferring the power-impulses of the cylinders to a crank shaft, and to provide such a means which is adaptable to a multiple cylinder construction.

The means by which the foregoing and other objects are accomplished and the method of their accomplishment will readily be understood from the following specifications on reference to the accompanying drawings, in which—

Fig. 1 is a sectional elevation at right angles to the crank shaft taken on the line I—I of Figs. 3 and 4, and along the longitudinal center line of one group of the cylinders of a multi-cylinder engine, in which all the cylinders are parallel.

Fig. 2 is a sectional elevation taken along the line II—II of Figs. 3 and 4 and exterior to the same group of cylinders.

Fig. 3 is a sectional plan taken along the line III—III of Fig. 1.

Fig. 4 is a sectional elevation taken on the line IV—IV of Figs. 1, 2 and 3, being along the crank shaft.

Fig. 5 is an enlarged sectional elevation taken as on the line V—V of Fig. 4.

Fig. 6 is a sectional elevation of a modified 50 form of the engine in which two groups of cylinders are assembled with their longitudinal axes at right angles, the view being taken as on line VI—VI of Fig. 7.

Fig. 7 is a sectional elevation on an enlarged scale taken as on the line VII—VII of Fig. 6.

Fig. 8 is an elevation looking in the direction of the arrow VIII of Fig. 6.

Figs. 9 to 16, inclusive, are diagrammatical views showing the sequence of movements of the various parts of the engine shown in Figs. 1 to 5, inclusive, a single cylinder, a single piston, and a single piston rod having been substituted for the pairs of cylinders, piston and piston rods of Figs. 1 to 5.

Figs. 17 to 21, inclusive, show diagrammatically 10 the sequence of movements of the various parts of the type of engine shown in Figs. 6 to 8, inclusive, single pistons, cylinders and piston rods having been substituted for pairs as in Figs. 9 to 16.

Referring now to the drawings, and particularly to Figs. 1 to 5, inclusive, 10, 11 are a pair of opposed cylinders having a common longitudinal axis. 12, 13 are a second pair of cylinders having also a common axis, these four cylinders being connected to a crank case 14 and constituting one group of cylinders. 16, 17 and 18 are three of the four cylinders of a similar group of cylinders spaced laterally from the first group and connected to the same crank case 14 which, however, is shown in two parts, the longitudinal axes of the eight cylinders being parallel. The cylinders 10 to 13, inclusive, are respectively provided with pistons 19, 20, 21 and 22, these pistons having the usual piston rings 23. Cylinders 16 to 18, inclusive, and the unshown cylinder, are similarly provided with pistons, none of which are shown, but which are identical in construction and action with pistons 19 to 20, inclusive.

Piston 19 and 20 are connected together by a rigid piston rod 24 and pistons 21 and 22 by a similar piston rod 25. 26 is a block, preferably in two halves, in which a transcommuter-link pin 28 of a connecting rod, or transcommuter link 29, is journaled. 30 are bolts securing the piston rods 24 and 25 to the block 26 and securing the halves of the block together to complete the link pin bearing. At its opposite end the link has a bearing 31 which journals a crank pin 32. 33 is a crank disk which carries the crank pin 32 and is integral with, or securely fixed on, a crank shaft 34. The shaft 34 is journaled in a bearing 35, carried by one head 36 of the crank case 14.

The transcommuter pin 28 projects through the block 26 and has secured to its projecting end a transcommuter arm 37. The arm 37 is positioned parallel to the transcommuter link 29 and constrained to remain in such position, as by a key 38. 39 is a transcommuter arm pin

projecting transversely from the transcommuter arm 37 at its opposite end.

The effective length of the transcommuter link 28 is identical with the crank pin radius and the 5 effective length of the transcommuter arm 37 is double each of these.

The second group construction duplicates the first group, 58, 59 being the piston rods of the 10 second group of cylinders. 52 is the journal block; 53 the transcommuter link pin; 54 the transcommuter link; 55 the crank disk; 56 the crank pin; and 57 the crank shaft. 58 is the 15 crank shaft bearing and 59 the second crank case head. 60 indicates a fragmentary portion 20 of a propeller secured to the shaft 57. 61 is the transcommuter arm duplicating the arm 37, and 62 the transcommuter arm pin corresponding to the pin 38. Both the pin 38 and the pin 62 are hollow. They are coupled together, as by a bolt 25 63 on which at least one of them is free to turn, it being readily seen that a stud, secured in one of the pins and journalled in the other thereof, will accomplish the same purpose. The two pins 38 and 62 so coupled are preferably journalled 30 in a shoe 64, which shoe is slidably mounted between guides 65, which guides are disposed at right angles to the longitudinal axes of the cylinders and of the crank shafts. The guides 65 are preferably carried by a diaphragm 66 which is 35 disposed between the two halves of the crank case 14, these halves being flanged for the purpose. The crank case heads 36 and 59 and the intermediate diaphragm may be secured in any usual or well known manner, as by bolts, which to 40 reduce the detail are not here shown.

70 and 71 are half time shafts for the group of cylinders 10 to 13, inclusive, and 72, 73 half-time shafts for the other group of cylinders.

Mounted on the shaft 70 and secured, as by 45 a key 74, is a gear 75, and similarly mounted and secured on the shaft 71 is a gear 76, which gears both mesh with a pinion 77 of one half relative pitch diameter which is mounted on shaft 34 and secured thereto by a key 78. 50 Similar gears 79 and 80 and meshing pinion 81 are respectively secured on the half-time shafts 72 and 73 and the shaft 57. 82 is a distributor driven by the half-time shaft 70, which distributor is suitably wired to spark plugs 83 on the 55 cylinders 10 to 13, inclusive. 84 is a second distributor suitably wired to spark plugs 85 on the other group of cylinders.

90 are cams mounted on the shaft 70, these 60 cams being secured as by the joint key 91. 92 are spacer disks alternating with the cams 90. 93 are similar cams similarly secured on the shaft 71, and 94 the alternating spacers. 95 is an enclosing housing. The cams 90 and 93 actuate the valves of the cylinders 10 to 13, inclusive, and 65 a similar group of cams mounted on the half-time shafts 72, 73, actuate the valves of the opposite group of cylinders. 100 is a pivot pin on which is mounted a pair of levers, 101, these levers depending past the cams 93. Preferably 70 each of these levers has a heel 102, which projects between a pair of the disks 92 to position the lever along the pin 100, these heels not projecting into the path of the cams 90. The lower end of each lever lies between a pair of the disks 94 and against a cam 93. 103 is an oppositely disposed pivot pin from which an additional pair of levers 104 depend, these levers lying on the opposite sides of the cams 93 and alternating 75 with the levers 101, so that levers 104 engage

others of the cam 93 than those engaged by the levers 101.

106 and 107 are additional pivot pins from which similar pairs of levers, 108, 109, extend upward on opposite sides of the cams 90. Each 10 of the levers is connected by a link 110, a rod 111, which passes out of the housing 95 through a stuffing box 112, and by a flexible cable 113 to a rocker arm 114, which operatively engages the end of a valve stem 115, a similar cable and 15 rocker arm being provided obviously for each valve. 116 is a bracket supported at one end by the housing 95 and at the opposite end by a valve stem housing 117, which projects from the head 118 of the cylinder 12, similar valve housings 20 projecting from each of the other heads and similarly supporting additional brackets. 119 is a pivot pin for the rocker arm 114 and for a second rocker arm 120, these two arms operating the intake and exhaust valves of the cylinder 12 25 and being guided in their movements by the housing 117.

The engine here shown is the four cycle type, each cylinder having an exhaust valve 130 and an intake valve 131. 132 are the exhaust pipes 25 and 133 the intake manifolds, which lead from the carburetors 134 to the cylinders.

In Figs. 6 to 8, inclusive, two groups of cylinders have been arranged with their axes at right angles instead of parallel, as before described. 30 In this arrangement, designated as X motor, the cylinders, and many of the other parts, may be identical in construction and function with those heretofore described, and these parts have been given the same numbers with the letter "A" as 35 a suffix.

10A, 11A, 12A and 13A are the cylinders constituting one group, and 15A, 16A, 17A and 18A are the cylinders constituting a second group at right angles, these groups being connected to a joint crank case 14A. 19A, 20A, 21A and 22A are the pistons of the first group, the pistons of the second group not being shown. Pistons 19A and 20A are connected together by a rigid piston rod 24A, and the pistons 21A and 22A by a similar 45 rod 25A. 26A is the journal block, the two piston rods and the block being rigidly secured together by bolts 30A. 32A is the crank pin, 33A the crank disk which carries this pin, and 34A the crank shaft which is journalled in the bearing 50 35A, carried by one head 36A of the crank case 14A.

50A, 51A are the piston rods of the second group of cylinders 15A to 18A; 52A is the halved journal block. 55A is the crank disk; 56A the crank pin, which has the same throw as the crank 55 pin 32A; 57A the crank shaft and 59A the second crank case head.

The piston rods 24A, 25A are connected to the crank pin 32A through a transcommuter link 150, one end of which is journalled on the crank pin 32A. Integral with, and projecting from the opposite end of the link 150, is a transcommuter link pin 151, which is journalled in the journal block 26A.

The piston rods 50A, 51A are connected to the crank pin 56A through a transcommuter link 152, one end of which journals on the crank pin 56A. Integral with the opposite end of the link 152 is a transcommuter link pin 153, which is 70 journalled in the journal block 52A.

Link pins 151 and 153 are integrally secured to a transcommuter bar 154, this bar and the links 150, 152 being thereby joined into a unitary transcommuter. In this transcommuter the center 75

lines of the pins 151 and 153 and of the bearings for the crank pins 32A, 56A lie in the same plane and are parallel, the distance between the pin 151 and its related bearing for the pin 32A, and the distance between the pin 153 and its related bearing for the pin 56A, are each equal to the crank radius of these pins, and the distance between the pins 151 and 153 is equal to twice this radius.

10 The valve and ignition mechanism is identical with that before described and need not be further described.

It will be understood that with both types each group of four cylinders functions as a complete unit and that an engine of this type may be so built. It will also be understood that single opposed cylinders, having a common longitudinal axis, may be used instead of opposed pairs as shown, particularly where two cycle or steam is used. Advantage has been taken of this fact to simplify the diagrammatic drawings, Figs. 9 to 16, inclusive, of the parallel cylinder type and the drawings 17 to 21, inclusive, of the X motor type. In Figs. 9 to 16, the pair of cylinders 10,

25 12, are represented by a single cylinder C, cylinders 11, 13 by cylinder D, cylinders 15, 17 by cylinder E, and cylinder 16, 18 by cylinder F; similarly each pair of pistons is represented by a single piston G, H, J, and K, respectively, and each pair of piston rods by a single rod N and M, respectively. The crank disks 33 and 55 have been replaced by their equivalent crank arms similarly numbered.

In Figs. 17 to 21, inclusive, N, P, Q and R are 35 cylinders representing the pairs of cylinders; S, T, U and V the pistons and W and Y the piston rods.

Crank arms 33A and 55A have been used instead of the equivalent crank disks.

40 Operation of parallel cylinder motor

In operation, referring to Fig. 1, the rigid assembly comprising the four pistons, 19 to 22, the piston rods 24 and 25 and the journal block 26 are shown as starting toward the left, as under the impulse from a fired charge in the cylinder 11. At the same time a charge is being compressed in cylinder 10, a charge is being drawn into cylinder 13 through intake valve 131, and a spent charge is being exhausted from cylinder 12. As the block 26 moves toward the crank shaft 34, the transcommuter link 29 forces the crank pin 32 upward turning the shaft 34. Concurrently the shoe 64 is moved by the pin 39 outward between the guides 65, and at right angles to the line of piston travel. At one end of the stroke either the cylinder 20 or 22 gives a power-impulse, and at the opposite end, one of the pistons 19, 21, gives an impulse.

60 The complete cycle of operation thus accomplished is diagrammatically shown in Figs. 9 to 16, inclusive. In Fig. 9 all the pistons are at one or the other ends of their respective strokes, piston H and piston J being ready to move toward the crank shafts 34, 57, and pistons G and K being correspondingly in position, to begin movement away from the shafts. The crank arms 33 and 55 are on dead center and all pins in line. As movement begins piston-impulse acting 70 through transcommuter links 29 and 54 on crank arms 33, 55, turns them respectively counter clockwise and clockwise. In Fig. 10, the block 26 and the pin journalled therein (pin 28, Figs. 1 and 3), have been moved by piston H and rod L toward the crank shaft 34 and through the trans-

commuter link 29 have moved the crank arm 33, forty-five degrees from its first shown position. Similarly piston J, through rod M, has moved block 52 and its journalled pin toward the crank shaft 57 (aligned with shaft 34), and through the transcommuter link 54 has moved the arm forty-five degrees also, though in opposite relative direction. In these movements transcommuter arms 37 and 61 have shifted the transcommuter arm pins 39 and 62 outward along the 10 guides 65, and the pins 39 and 62 being coupled together by the bolt 63 (Fig. 3) and being journalled in a joint shoe 64, are compelled to move concurrently and to interchange power-impulses and timing between the two piston groups and 15 their shafts, providing a means whereby the power of both groups may be available from either the shaft 34 or the shaft 57.

In Fig. 11 the two crank arms 33, 55 reach a 20 ninety degree position and the transcommuter arm pins 39, 62 the outer limit of their travel in the guides 65; the pistons have reached mid-stroke and are travelling twice as fast as the crank pins.

In Fig. 12 both crank shafts have travelled one 25 hundred and thirty-five degrees, and the coupled transcommuter-arm pins 39, 62 are returning along the guides 65.

In Fig. 13 one hundred and eighty degrees have 30 been reached, the transcommuter-arm pins 39, 62 are aligned with the crank shafts 34, 57 and moving from above to below the same, and the power-impulses have transferred from cylinder D to cylinder C, and from cylinder E to cylinder F.

In Figs. 14, 15 and 16 the cycle continues, returning to that shown in Fig. 9, the action corresponding to that of Figs. 9 to 12, respectively.

Referring to Fig. 11 or Fig. 15 (the crank arms being at ninety degrees), it will be noted that the 40 transcommuter link 29 overlies the crank arm 33, so that the transcommuter link pin journalled in the block 26 (the pin 28 of Figs. 1 and 3) is concentric with the shaft 34. Should a single cylinder group engine stop in such position, it 45 would be possible, but for the transcommuter arm 37, and the guides 65, to turn the shaft 34, the crank arm 33 and the link 29, the link pin turning in the block 26 and transmitting no movement to the piston rods or pistons, though obviously movement of the pistons would shift the block 26 and impart movement to the crank arm and shafts, and for proper action the transcommuter arm 37 is essential.

55 Operation of X motor

The rigid assembly comprising the four pistons 19A to 22A, the piston rods 24A and 25A and the journal block 26A, move as one unit under successive impulses on the four pistons, and the cross 60 positioned assembly moves similarly.

In Fig. 6 piston 20A is shown as moving downward and toward the left under the action of a fired charge; piston 19A as compressing an additional charge; piston 22A as drawing in a charge; and piston 21A as exhausting a fired charge, thus giving two impulses each revolution for these four cylinders and the additional four cylinders 15A to 18A giving two additional impulses per revolution.

In Fig. 17 piston S, acting through piston rod W on journal block 26A and transcommuter pin 151, transmits power through the transcommuter link 150 to the crank arm 35A and to the crank shaft 34A, and through the transcommuter bar

- 15A, the transcommuter link pin 153, the transcommuter link 152 to the crank arm 55A and the crank shaft 57A. Concurrently expansion in cylinder R acting through piston V and piston rod 5 Y on link pin 153, adds power in the same direction.

In Fig. 18 the crank arms 33A, 55A have moved forty-five degrees from the position shown in Fig. 17, piston S continues its thrust at increasing 10 angularity with regard to transcommuter link 150, and piston V approaching the end of its stroke is still exerting thrust on pin 153.

In Fig. 19 crank shafts 33A and 55A are at 15 ninety degrees to their original position and all pins are again in alignment. Piston V has completed its stroke. Piston T is in firing position and becomes the primary power piston; and piston S is at mid-stroke exerting its thrust at right angles to transcommuter link 150.

20 In Fig. 20 the crank arms have completed one hundred and thirty-five degrees of movement from Fig. 17. Piston S is approaching completion of its expansion stroke. Piston T is acting under expansion. Piston U is approaching the end of the compression stroke.

25 In Fig. 21 the crank arm has completed one hundred and eighty degrees travel from the position shown in Fig. 17. Piston S has completed its expansion stroke, piston T is acting under expansion, piston U is in firing position and is the primary power piston; and piston V is on its compression stroke.

30 In the subsequent half cycle, pistons W and V successively become the primary power pistons establishing a continuous flow of power on both crank shafts.

What I claim is:

1. An engine, including a pair of axially aligned cylinders having each a piston reciprocally 40 mounted therein, a piston rod rigidly connecting said pistons, a bearing on said rod, a shaft, a crank member connected to said shaft, a crank pin carried by said member, a link having one end journalled on said crank pin and the opposite end rotatably secured to said piston rod bearing, the length of said link being equal to the crank radius, said link having a rigid extension of equal length, and a guide reciprocably receiving the end of said extension, said guide extending across the axis of said crank shaft at right angles to said axis and the axis of said cylinders and being a rigid part of said engines.

2. An engine, including four cylinders in axially aligned pairs, said cylinders having each a piston reciprocably mounted therein, piston rods, each rigidly connecting a said pair of pistons, a bearing rigidly secured between and securing said piston rods together, a shaft extending at right angles from the axes of said cylinders and rods, 50 crank means including a crank pin carried by said shaft, a link having its opposite ends journalled on said pin and in said bearing, said link and said crank means being of equal length, said link having a rigid arm of equal length extending beyond said crank pin; and a guide reciprocably receiving the end of said arm, said guide being at right angles to said shaft and to the axes of said cylinders and being a rigid part of said engine.

3. An engine including a crank case, a shaft journalled in said case, a crank member secured on said shaft, a crank pin projecting from said member, a pair of cylinders in axial alignment extending from opposite sides of said crank case 75 at right angles to said crank shaft, said cylin-

ders each having a piston reciprocably mounted therein, a piston rod extending past said crank member and rigidly connecting said pistons, a link journalled at one end on said crank pin and at its opposite end journalled to said piston rod, the length of said link being equal to the crank radius of said pin, a transcommuter arm of equal length with said link extending from said link beyond said crank; and guide means rigidly carried by said crank case, at right angles to said 10 crank shaft and to the axes of said cylinders, said means reciprocably receiving the end of said arm.

4. An engine, including a crank case having axially aligned bearings at its opposite ends, 15 crank shafts, each journalled in a said bearing, crank discs carried each by a said shaft, and crank pins of equal throw carried each by a said disk; four cylinders in axially aligned pairs spaced apart, extending along parallel lines outward from said crank case, pistons reciprocably mounted, one in each said cylinder, a pair of piston rods, one for each said aligned pair of cylinders, each rod rigidly connecting the pistons of its respective said cylinders, bearing means, 25 each carried by a said piston rod intermediate its length, transcommuter links, each equal in length to the throw radius of said crank pins, each connecting a said crank pin and a said piston bearing, said links having each a rigidly extending transcommuter arm of equal length, and means pivotally connecting the extended ends of said arms.

5. An engine, including a crank case having axially aligned bearings at its opposite ends, 35 crank shafts, each journalled in a said bearing, crank members carried each by a said shaft, and crank pins of equal throw carried each by a said member; four cylinders in axially aligned pairs spaced apart, extending along parallel lines outward from said crank case, pistons reciprocably mounted, one in each said cylinder, a pair of piston rods, one for each said aligned pair of cylinders, each rod rigidly connecting the pistons of its respective said cylinders, bearing means, 40 each carried by a said piston rod intermediate its length, transcommuter links, each equal in length to the throw radius of said crank pins, each connecting a said crank pin and a said piston bearing, said links having each a rigidly extending transcommuter arm of equal length, means pivotally connecting the extended ends of said arms, and guide means rigidly secured to said crank case at right angles to said cylinder axes and crank shafts, said means extending laterally outward from the axis of said crank shafts and reciprocably receiving said arm connecting means.

6. An engine, including a crank case having axially aligned bearings at its opposite ends, crank 60 shafts, each journalled in a said bearing, crank members carried each by a said shaft, and crank pins of equal throw carried each by a said member; four cylinders in axially aligned pairs spaced apart, extending along parallel lines outward from said crank case, pistons reciprocably mounted, one in each said cylinder, a pair of piston rods, one rod for each said aligned pair of cylinders, each rigidly connecting the pistons of its respective said cylinders, journal bearings, each 65 carried by a said piston rod intermediate its length, transcommuter links, each equal in length to the throw radius of said crank pin, said links being journalled respectively each on a said crank pin and having each a transcommuter pin 70 75

- journalled in a said piston bearing, said links having each a rigidly extending transcommuter arm, said arms being of equal length, and rigidly secured each on a said transcommuter pin 5 and respectively extending each from its said pin parallel with said transcommuter link twice the length of said link, each said transcommuter arm having a hollow pin projecting laterally at its inner end toward the complementary pin of 10 the other said arm, a bolt passing through said hollow pins and rotatably securing said pins together; a guide rigidly carried by said crank case and disposed between said arms, said guide being at right angles to said shafts and said piston rods, and a shoe reciprocably mounted in 15 said guide and journalled on said hollow pins.
7. An engine, including a crank case having axially aligned bearings extending from opposite ends thereof, shafts, each journalled in a said 20 bearing, each said shaft having a crank disk within said case and a crank pin projecting from said disk, the crank radius of said pins being equal; a first pair of axially aligned cylinders secured to and projecting from said crank case 25 in a plane at right angles to said crank shafts, a complementary pair of axially aligned cylinders secured to and projecting from said case in a spaced parallel plane, the said complementary cylinder axes being at right angles to the first 30 said cylinder axes; each said cylinder having a piston reciprocably mounted therein; a pair of piston rods, one for each said aligned pair of cylinders, each said piston rod rigidly connecting its related pair of pistons, each said piston 35 rod carrying a bearing intermediate its length, a pair of parallel transcommuter links, each lying between a said crank disk and a related said piston rod and being journalled on a said crank pin, said links having a rigidly extending transcommuter pin extending therefrom through its 40 respective said piston rod bearing, the effective length of said links being equal and equal to the crank radius; and a transcommuter connector rigidly secured to and joining the projecting ends 45 of said transcommuter pins, said connector lying between said piston rods and parallel to both said transcommuter links.
8. An engine, including a crank case having axially aligned bearings extending from opposite ends thereof, crank shafts, each journalled 50 in said bearings, each said shaft having a crank disk within said case and a crank pin projecting from said disk, the throw of said pins being equal, a first pair of axially aligned cylinders secured to and projecting from said case in a spaced parallel plane, the said cylinder axes being at right angles to the first cylinder axes; each said cylinder having a piston reciprocably mounted therein; a pair of piston rods, one for each said aligned pair of cylinders, each said piston rod rigidly connecting its related pair of pistons, and having a journal bearing intermediate its length; a pair of links in parallel, each journalled on a said crank pin and having a pin journalled in a respective said journal bearing, the effective length of said links being each equal to a crank pin radius, and means rigidly secured to said link pins, compelling said links to remain in parallelism, the effective length of said means equalling a crank diameter.

CLIFTON F. SMITH.
